UNITED STATES PATENT OFFICE

JOHANNES OLSEN JORDELL, OF OSLO, NORWAY

SKI FASTENING

Application filed October 15, 1928, Serial No. 312,641, and in Norway October 19, 1927.

The present invention relates to improvements in ski-fastenings, whereby it is possible in a quick and easy manner to place and to remove the back-fastening from the ski, and the invention is especially characterized by the fact that the ends of the back-fastening are pivotally mounted each on one of two in each other slideable and lockable members, which are from opposite sides inserted through a hole or slot in the ski.

A preferred form of the invention is illustrated in the accompanying drawing, in which:

Figure 1 is a side view of a part of a ski with the device.

Figure 2 is a plan view of the two parts of the device.

Figure 3 is a plan view of a toe-iron before the ears have been bent up.

Figure 4 is a cross section taken as indicated at line A—A of Figure 3.

Fig. 5 is a top plan view of a part of a ski with the device applied thereto.

Fig. 6 is a longitudinal sectional view through the coacting locking members,

Fig. 7 is a transverse sectional view through one of the members, and

Fig. 8 is a transverse sectional view through the other of the members.

The back-strap 1 is at each end provided with a metallic member 2, which is pivotally mounted on upright ears 3 and 4 on iron-bands 5 and 6 respectively, either by riveting as shown in the drawing.

The iron-band 5 has dovetailed cross section (Fig. 7), and the iron-band 6 has a corresponding form (Fig. 8), so that it is slideable in the iron-band 5. Inside the iron-band 6 a plate-spring 7 is

40 riveted, which is adapted to engage with a number of teeth 8, provided inside the iron-band 5.

When a back-fastening according to the invention is to be fastened to the ski, for instance by a toe-iron as shown in Figure 1, the iron-band 5 is inserted in a slot or opening 11 in the ski between the two horizontal parts of the toe-iron which latter is accommodated in a transverse slot in the ski 45 proper. Then the iron-band 6 is inserted

in the iron-band 5 from the opposite side, and it is then obvious that the tip of the spring 7 will come in engagement with the teeth 8, so that the iron-bands can not be drawn from each other without special means. If 55 for any reason it is wanted to loosen the back-fastening from the ski, a suitable device, for instance a thin metal strip S, (Fig. 6), is inserted between the iron-bands 5—6, so that the engagement between the spring 60 7 and the tooth 8 is released and the other slots are overlapped, whereupon the iron-bands can be drawn from each other.

The toe-iron 9, shown in the drawing, has along the edge lying behind the iron bands 65 5—6 a part 10 bent downwards, so that a steady rest for the iron band 5 is obtained, simultaneously as a through-slot 11 under the toe-iron is formed for placing a cross-strap 12, which is fastened to the 70 buckles 13 of the back-strap 1, (Fig. 3).

The embodiment shown in the drawing is only given as an example, as alterations may be made without departing from the scope of the invention. For instance the guiding devices for the iron bands may be different from those shown in the drawing, and the automatic locking by the displacement of the iron-bands in each other may be different from that shown, without departing from the scope 80 of the invention.

What I claim is:

1. A ski-fastener of the character described, including in combination with a ski having a transverse slot therein and a back-fastening strap, of interchangeable and lockable members slidably and removably mounted in said slot and each having one of the ends of the back-fastening strap secured thereto.

2. A ski-fastening device in accordance 90 with claim 1, wherein both of the members are in the form of iron bands of dove-tailed shape in cross section and are slidably telescoped one within the other, one of said members being provided with a series of teeth, 95 and a plate spring on the other of said members for engagement with the teeth of the first member so that the members cannot be accidentally drawn from each other.

3. A ski-fastening device in accordance 100

with claim 1, wherein the outer ends of the members are each provided with an upright ear to which the adjacent ends of the back-strap are pivotally connected.

4. A ski-fastening device according to claim 1 and in combination therewith, a toe-iron arranged through the slot with the terminals extending above the upper surface of the ski, a downwardly bent portion adjacent the bottom surface of the slot to hold the upper surface of the medial portion of the toe-plate against the opposite surface of the slot in the ski, said bent part coacting with the adjacent end of the slot to leave a passage adapted to accommodate a cross strap, and the medial portion of the toe-plate being also provided with a through slot for receiving the interengageable and lockable members, substantially as and for the purposes set forth.

20 In testimony whereof I have signed my name to this specification.

JOHANNES OLSEN JORDELL.
